LATCH

Charles Thomas Hammond, Thornton Heath, England,
assignor to Redwing Limited, Thornton Heath, Croy-
don, England

Application August 4, 1953, Serial No. 26,267.

Claims priority, application Great Britain July 13, 1953

Term of patent 14 years

(Cl. D50—5)

FIG. 1.

FIG. 2.

FIG. 3.

FIG. 4.

To all whom it may concern:

Be it known that I, Charles Thomas Hammond, a British subject, residing at 206 Mersham Road, Thornton Heath, Surrey, England, have invented a new, original, and ornamental Design for a Latch, of which the following is a specification, reference being had to the accompanying drawing, forming a part hereof.

In the drawings:

Figure 1 is a front perspective view from above and to one side of a latch showing my new design;

Figure 2 is an elevation from the other side;

Figure 3 is a front elevation; and

Figure 4 is an underneath plan.

I claim:

The ornamental design for a latch, as shown.
